UNITED STATES PATENT OFFICE

FRED GITZENDANNER, OF NEW YORK, N. Y.

SELF-ADJUSTING FEED ROLLER

Application filed April 21, 1930. Serial No. 445,849.

My invention relates to rollers for feeding paper, fabric and similar materials. It is well known that the feeding of thin materials, such as paper for example, involves many difficulties when handled with the ordinary straight rollers now in use. If such rollers are not perfectly parallel to each other the material is fed faster at one edge than the other. If the rollers are not perfectly straight or exactly concentric uneven feeding likewise results. If any foreign matter should accidentally adhere to the material, or the material should contain a fold for example, and thus carried between the rollers, uneven feeding, or even complete distortion, of the material may result.

The main object of the present invention is to provide a feed roller which will automatically adjust itself to any irregularities in parallelism, concentricity, or other defects in its companion roller, or in the material being fed, and thus insure an even rate of feed under all conditions. This is of great importance when feeding paper or other materials which must be accurately registered, as in printing for example.

Another object is to provide a feed roller containing a plurality of units which can be spaced at various distances so as to engage the material only at such places as may be desirable. A further object is to provide a feed roller in which the pressure of each unit may be adjusted to the requirements of the particular material being fed. A still further object is to provide a feed roller which may be installed and used on any machine using straight rollers without necessitating any change or alteration in such machine, and which can be manufactured and installed at a comparatively low cost.

These and various other objects and advantages will be readily understood from the following description and from the accompanying drawings of a preferred embodiment in which, however, various modifications may be made without departing from the scope of the invention. In the drawings

Fig. 1 is a plan view of the improved feed roller, shown with its straight companion roller;

Fig. 2 is a cross-sectional, end view of Fig. 1, taken on line 2-2;

Fig. 3 is a cross-sectional, end view, taken on line 3-3, Fig. 1; and

Fig. 4 is a cross-sectional, side view of one of the units making up the roller.

Referring now to all the views, simultaneously, an ordinary, straight roller is shown at 10. The improved feed roller consists of a shaft 11 upon which a number of units C, D, and E are secured against rotation by set screws 12. These units are all alike and each consists of a sleeve 13 made with a large head 14 in which the screw 12 is inserted. The front end of the sleeve is threaded and on this thread a nut 15 and a lock nut 16 are attached.

A roller 17, of larger diameter than the head 14 and with a concentric bore 18 of larger diameter than the outside diameter of the sleeve, is rotatably mounted on the sleeve. As the bore is larger than the sleeve, the roller is free to "float" on the sleeve. Concentric recesses are turned in both sides of the roller and in these recesses fibre discs 19 and 20 are placed. The discs are thicker than the depth of the recesses, are free to rotate in the recesses, and are provided with holes of the same size as the bore in the roller.

A collar 21 is slidably mounted on the sleeve but prevented from rotating by a key 22 which is inserted in the sleeve. The roller and the two fibre discs are held between the head 14 and the collar 21 in the following manner. A plurality of holes are drilled in one side of the collar and compression springs 23 each has one of its ends inserted in, and guided by these holes. The other ends of the springs abut against a washer 24 to which an aligning pin 25, which slides in a hole 26 in the collar, is riveted. By thus preventing the washer from rotating, all danger of the springs jamming on the edges of the holes is removed. In all the views the center line of the shaft 11 is indicated by the letter A, while the center line of the roller and the fibre discs is indicated by the letter B.

The nuts 15 and 16 may either be knurled so that they can be tightened by hand, pro-

vided with holes 27 for use with a spanner wrench, or provided with any other suitable tightening means. It is evident that by manipulating these nuts the friction on the fibre discs and the roller may be varied to meet the required condition. It is also evident that, as the shaft 11 rotates, the roller 17 is presented eccentrically to the material 28 as it passes over the companion roller 10 and that the roller is forced backwards, or towards the sleeve, to accommodate the thickness of the material at the particular point of contact, thus feeding the material at an even rate no matter what its condition, or that of the roller 10, may be at that point.

While the units C, D, and E are shown assembled in contact with each other on the shaft 11, it will be understood that they may be secured at any points along the shaft. 20 This makes it possible to engage the material at any desired point, as for example the margins and intermediate spaces of paper just printed. It will be noted that practically all the wear will be on the fibre discs 25 and that these may be replaced at low cost. Furthermore these discs give the rollers 17 a smooth and easy movement.

Having described my invention and its use, what I claim as new and wish to protect by Letters Patent is:

1. In a feed roller unit, a sleeve having an enlarged head, a roller having a larger outside diameter than that of said head and a bore of a larger diameter than the outside 35 diameter of the sleeve, a collar slidably mounted on the sleeve, and means mounted upon the sleeve for clamping said roller yieldingly between said head and said collar.

2. In a feed roller unit, a sleeve having an 40 enlarged head, a roller having a larger outside diameter than that of said head and a bore of a larger diameter than the outside diameter of the sleeve, a collar slidably mounted on the sleeve, and spring-actuated 45 means mounted upon the sleeve for clamping said roller yieldingly between said head and said collar.

3. In a feed roller unit, a sleeve having an 50 enlarged head, a roller having a larger diameter than that of said head and a bore of a larger diameter than the outside diameter of the sleeve, a collar slidably mounted on said sleeve, and adjustable spring-actuated means mounted upon the sleeve for clamping said 55 roller yieldingly between said head and said collar whereby the friction between these parts may be varied.

4. In a feed roller unit, a sleeve having an 60 enlarged head, a roller having a larger diameter than that of said head and a bore of a larger diameter than the outside diameter of the sleeve, a collar slidably mounted on the sleeve, spring-actuated means mounted upon the sleeve for clamping said roller 65 yieldingly between said head and said collar,

and discs interposed between the head and the roller and the roller and the collar to facilitate the movement of the roller.

5. In a feed roller unit, a sleeve having an enlarged head, a roller having a larger diameter than that of the said head and a bore of a larger diameter than the outside diameter of the sleeve, a collar slidably mounted on the sleeve, spring-actuated means mounted upon the sleeve for clamping said collar between said head and said collar, and fibre discs interposed between the head and the roller and the roller and the collar to facilitate the movement of the roller and receive the main wear during the 75 80 85 90 95 100 105 110 115 120 125 130 operation of the feed roller.

6. In a feed roller, a shaft, a plurality of units secured and adjustable lengthwise of said shaft and each consisting of, a sleeve having an enlarged head, a roller having a larger diameter than the outside diameter of said head and a bore of a larger size than the diameter of the outside of said sleeve, a collar slidably mounted on the sleeve, and spring-actuated means mounted upon the sleeve for clamping said roller yieldingly between said head and said collar.

7. In a feed roller, a shaft, a plurality of units secured on said shaft and each consisting of a sleeve having an enlarged head, a roller having a larger outside diameter than that of said head and a bore of a large size than the outside diameter of the sleeve, a collar slidably mounted on the sleeve, and means mounted upon the sleeve for clamping said roller yieldingly between said head and said collar.
